SUCTION CLEANER

Dale C. Gerber and Edward R. Swann, North Canton, Ohio, assignors to The Hoover Company, North Canton, Ohio, a corporation of Ohio

Application July 15, 1939, Serial No. 284,578

12 Claims. (Cl. 15—182)

The present invention relates to suction cleaners in general and particularly to new and novel adjustable agitating brushes in rotary agitators for suction cleaners. More specifically the invention comprises a new and improved rotary agitator for a suction cleaner embodying an adjustable agitating element which is radially movable to compensate for decrease in radial extension with wear.

It is an object of the present invention to provide a new and improved suction cleaner. It is another object of the invention to provide a new and improved rotary agitator for a suction cleaner. It is another object of the invention to provide a new and improved adjustable agitating element for a rotary agitator of a suction cleaner. A still further object of the invention is to provide a new and improved rotary agitator embodying a reversible, helically extending brush which is adjustable to compensate for brush wear. Still another object of the invention is to provide a simple, economically manufactured replaceable brush element which cooperates with the brush seat in the rotary agitator in a new and novel manner. These and other more specific objects will appear upon reading the following specification and claims and upon considering in connection therewith the attached drawings to which they relate.

Referring now to the drawings in which preferred embodiments of the invention are disclosed:

Figure 1 is a front elevation of a modern suction cleaner embodying an agitator constructed in accordance with the present invention, certain parts of the casing being broken away;

Figure 2 is a side view of an agitator constructed in accordance with the present invention with certain parts of the agitator body broken away and shown in section, the brush being positioned in its inner radial position;

Figure 3 is a section upon the line 3—3 of Figure 2;

Figure 4 is a view similar to Figure 2 but with the brush adjusted to the worn brush position or outer radial position;

Figure 5 is a section through the brush and brush seat being taken upon the line 5—5 of Figure 2;

Figure 6 is a section upon the line 6—6 of Figure 2;

Figure 7 is a section upon the line 7—7 of Figure 2;

Figure 8 is a perspective view of the brush seat removed from the agitator body;

Figure 9 is a view in perspective of the brush element itself;

Figure 10 is a side elevation of one-half of an agitator constructed in accordance with the second embodiment of the invention, certain parts being broken away and the brush being positioned in the new brush position or inner radial position;

Figure 11 is a view similar to Figure 10 but with the brush positioned in its outer radial position or worn brush position;

Figure 12 is a section upon the line 12—12 of Figure 10;

Figure 13 is a top view of the brush back of the second embodiment of the invention.

In the drawings a modern suction cleaner is illustrated and is seen to comprise a nozzle 1 which is interiorly connected through a passage-way 2 to a fan chamber 3 which houses a suction-creating fan 4 carried by the lower end of the motor shaft 5. The motor is not shown but is positioned immediately above the fan chamber 3 in the motor housing 6. A power-transmitting belt 7 connects the lower end of motor shaft 5 to the rotary agitator 10 which is rotatably positioned within the nozzle 1 and which will be hereinafter fully described. The cleaner is movably supported upon wheels 8 and, as in the usual cleaner, a pivoted handle 9 is provided by which the operator can exert the necessary propelling and guiding forces.

Referring now to Figures 2 to 9, inclusive, in particular, the agitator constructed in accordance with the first preferred embodiment of the invention is illustrated. Agitator 10 is seen to comprise an elongated hollow cylindrical body 11 which is formed substantially midway of its length with a recessed grooved portion forming a pulley 12. At each of its ends is positioned a thread guard 13 carried by longitudinally extending stationary supporting shaft 14 by which the agitator is rotatably mounted within the cleaner nozzle.

Upon the surface of the agitator body 11 is positioned a helically extending rigid beater bar 16 which is seen to have a radial projection beyond the normal circumference of the agitator. As the two halves of the agitator body are substantially identical only one half thereof will be described. Spaced substantially 180 degrees circumferentially from the beater bar upon each side of the centrally located pulley 12 is a brush seat 18 which is seen to be formed of parallel side walls 19 which extend angularly across the agitator body and which in their radial di-

mensions are parallel to a single radius line R—R, as illustrated in Figure 6. It is seen, therefore, that each side wall of each brush seat is a straight wall parallel to the opposite side wall. A bottom curved wall 20 extends between the side walls 19 while at the ends thereof are parallel end walls 21 which lie in planes extending perpendicular to the axis of the agitator body 11 and to the axis of rotation 14. The walls 19, therefore, intersect the plane of the end walls 21 at an angle less than 90 degrees.

The brush seat 18 is preferably formed as a separate stamped or molded element, as indicated in Figure 8, there being an overturned rim 22 around the top of the side and end walls which is adapted to be secured, as by welding, to the inner face of the agitator body 11.

The end walls 21 of the brush seat are cut out in a definite manner to permit of brush adjustment. At the outer end the brush seat is formed with separated lower shoulders 24, there being an intermediate shoulder 25 at a higher elevation therebetween. At the opposite end of the brush back is a single shoulder 26 which is at a height in the brush seat halfway between the shoulders 24 and 25. The brush seat construction is completed by the presence of elongated leaf springs 27 which are centrally fastened to the bottom wall 20 of the seat and which extend to the ends thereof where they are adapted to contact the removable brush element now to be described.

Removably positioned within the brush seat 18 is the brush element 30 comprising a helically extending row of brush tufts carried by a rigid back 31 formed with parallel side walls 32 spaced apart a distance slightly less than the walls 19 of the brush seat and by parallel end walls 33, the end walls being related to the side walls in the same manner as the end walls of the brush seat are related to the side walls thereof. Each end wall 33 is provided with an abutment shoulder, indicated by the reference character 35 and at the opposite end by the reference character 36. Shoulder 35 is positioned higher upon the end plate 33 than is shoulder 36 and is relatively narrow so that it is adapted to extend between the shoulders 24 at the outer end of the brush seat and into contact with the upper shoulder 25. The wide shoulder 36 is at a lower height on the brush back than shoulder 35 and is sufficiently wide that it extends entirely across the brush seat between the shoulders 24, so that it cannot pass therebetween and into contact with the shoulder 25. The vertical distance separating the shoulders 35 and 36 is equal to one-half the distance separating shoulders 24 and 25, that is, equal to the vertical distance separating either shoulder 24 or shoulder 25 from intermediate shoulder 26.

The relationship is such that the brush 30 is adapted to be positioned within the seat 18 in either of two reversed positions. In the one position the wide brush shoulder 36 will underlie the low seat shoulders 24 while at the opposite end the high, narrow brush shoulder 35 abuts the intermediate seat shoulder 26. In this position, that illustrated in Figure 2, the brush is in its new brush position which is also its inner radial position. The brush is also adapted to be reversed in which position the upper narrow shoulder 35 would extend between shoulders 24, 24 and would contact the upper seat shoulder 25 at the outer end of the brush seat, while the lower wide brush shoulder 36 would contact the intermediate

seat shoulder 26. Obviously each end of the brush back is advanced outwardly a distance equal to one-half that separating the shoulders 24 and 25, the intermediate shoulder 26 being positioned half way therebetween. This second adjustment is the worn brush position or the outer radial position.

In either of its two positions the contact with the bottom of the rigid brush back 31 by the flexible leaf springs 27 causes the brush to be held radially outward and into contact with the overlying shoulders. When the agitator is rotating, of course, centrifugal force assists the leaf spring.

It is to be noted that the brush back 31 is made slightly shorter than the length of the brush seat 18 in order that it can be shifted lengthwise to displace one end shoulder from underneath the overlying seat shoulder to permit outward displacement of that end of the brush back from the agitator seat. Upon such displacement at one end it is possible to withdraw the entire brush to accomplish either reversal or replacement.

Referring now to Figures 10 to 13, inclusive, the second preferred embodiment of the invention is illustrated. The agitator is constructed in the manner of the first embodiment and the same reference characters are used to illustrate the same parts. The following differences are present, however. The adjusting shoulders 24, 25 and 26 at the ends of the brush seat have been eliminated and instead the end walls 21 are perfectly flat. Additionally, the leaf spring 27 has been omitted in this embodiment. Also, the brush back 31 is not provided with the shoulders 35 and 36 at the ends thereof. In this second embodiment, however, the rigid brush back 31, which is shaped as in the first embodiment, is formed on its underside with downwardly projecting abutment shoulders 40 which, in the new brush or inner radial position make contact with the surface of the bottom plate 20 of the brush seat 18. The latter is itself provided with upwardly projecting shoulders 41 and, when the brush is reversed to its worn brush or outer radial position, as illustrated in Figure 11, the downwardly projecting shoulders 40 on the rigid brush back contact and rest upon the upwardly projecting shoulders 41 upon the brush seat to give to the brush an upward or outer movement which is equal to the height of the seat shoulders 41. In this embodiment of the invention the brush is retained in the brush seat by means of screws 42 which pass downwardly through the ends of the brush back 31 and into threaded openings 43 formed in the brush seat. Reference to Figure 13 illustrates the shape of the brush element itself which is seen to have parallel side walls 32 and parallel ends walls 33. The brush element of the first embodiment is similarly shaped with the exception that the projecting shoulders 35 and 36 extend outwardly from the end walls 33.

The brush tufts of the agitator brush constructed in accordance with the present invention, when positioned in the agitator body, project substantially radially, relative to the axis of rotation at all points. The brush tufts are so mounted in the rigid brush back 31 that their ends lie in a helix about that axis. The formation and shape of the back permits of the economical manufacture of the brush by simple processes and the combination of the seating arrangement of the back and seat insures ease of adjustment. The construction also has the ad-

vantage that upon reversal and radial adjustment, maximum radial movement occurs at the brush center where the maximum wear occurs. As the brush seat side walls are parallel it is clear that the outward movement of the brush back therein will be a linear movement. Reference to Figures 5, 6 and 7 illustrates that upon reversal that part of the brush at the center will move in a truly radial direction to give a radial displacement of a while at the ends of the brush the radial movement will be less than a and will be a distance b or c which, at any point along the brush length will approximately equal $a \cos \alpha$ where α is the angle made by the brush tuft, the adjustment of which is being considered with the axial plane through the brush tuft having an adjustment a .

We claim:

1. A rotary agitator for a suction cleaner or the like comprising a cylindrical body, a brush seat extended angularly across said body within the normal periphery thereof and formed with straight sides each of which lies in a plane which extends parallel to a dividing plane between said sides, a brush including a rigid back formed with straight parallel sides positioned in said seat, and means to retain said brush in place.

2. A rotary agitator for a suction cleaner or the like comprising a cylindrical body, a brush seat extended angularly across said body within the normal periphery thereof and formed with sides lying in parallel planes, a brush reversibly positioned in said seat and including a rigid back formed with sides lying in straight parallel planes and bristles carried by said back and extended helically about an axis spaced from said back, and positioning means at the opposite ends of said back to position said back at different heights in said seat in reversed positions.

3. A rotary agitator for a suction cleaner or the like comprising a cylindrical body, a brush seat extended angularly across said body within the normal periphery thereof and formed with sides lying in parallel planes, a brush reversibly positioned in said seat and including a rigid back formed with sides lying in parallel planes and bristles carried by said back and extended helically about an axis spaced from said back, and cooperating positioning means in said seat and on said back to position said back at different heights in said seat in the reversed positions.

4. A brush element for a rotary agitator comprising an elongated back formed with straight parallel sides each of which lies in a single plane and with a top surface which describes a spiral longitudinally of said back, brush tufts seated in said surface and describing with their ends a spiral extending about a spaced axis.

5. A brush element for a rotary agitator comprising an elongated back formed with straight parallel longitudinally-extending sides each of which lies in a single plane and with a top surface which at any transverse section lies tangent to an imaginary cylinder, the points of tangency of said surface with said cylinder advancing circumferentially around said cylinder at a uniform rate along the length of said back, and brush bristles extended from said back describing with their ends a spiral about a spaced axis.

6. A brush element for a suction cleaner rotary agitator comprising bristles longitudinally arranged and describing at their outer ends a spiral which lies in an imaginary cylinder having

its major longitudinal axis spaced from said bristles; and a back mounting said bristles having parallel longitudinally-extending sides each of which lies in a single plane and parallel ends forming an angle of less than 90 degrees with said sides.

7. A brush element for a suction cleaner rotary agitator comprising bristles longitudinally arranged and describing at their outer ends a spiral which lies in an imaginary cylinder having its major longitudinal axis spaced from said bristles; and a back mounting said bristles having parallel longitudinally-extending sides each of which lies in a single plane, parallel ends forming an angle of less than 90 degrees with said sides and positioning means on the ends.

8. A brush element for a suction cleaner rotary agitator comprising bristles longitudinally arranged and describing at their outer ends a spiral which lies in an imaginary cylinder having its major longitudinal axis spaced from said bristles; and a back mounting said bristles having parallel longitudinally-extending sides each of which lies in a single plane, parallel ends forming an angle of less than 90 degrees with said sides and projecting abutment shoulders at different heights on the opposite ends thereof.

9. A brush element for a suction cleaner rotary agitator comprising bristles longitudinally arranged and describing at their outer ends a spiral which lies in an imaginary cylinder having its major longitudinal axis spaced from said bristles; and a back mounting said bristles having parallel longitudinally-extending sides each of which lies in a single plane, parallel ends forming an angle of less than 90 degrees with said sides, and downwardly projecting positioning abutments on the underside of said back.

10. A rotary agitator for a suction cleaner or the like comprising a cylindrical body, a brush seat with longitudinally straight and parallel sides extended angularly across said body within the normal periphery thereof each side lying in a single plane, a brush including a rigid back with longitudinally straight and parallel sides each lying in a single plane extended angularly across said body and positioned in said seat, and means to position said rigid back at different heights in said seat in the reversed positions.

11. A rotary agitator for a suction cleaner or the like comprising a cylindrical body, a brush seat with straight sides lying in parallel planes extended angularly across said body and extending in a truly radial direction in one section only, a brush including a rigid back extended angularly across said body in said seat, said brush being adapted to seat reversibly in said seat, means to secure said brush at different distances from the axis of rotation of said body in the reversed relationships, characterized in that one part only of said brush is adjusted in a truly radial direction upon being reversed and all other parts thereof are moved a lesser distance than said radially moving part.

12. A rotary agitator for a suction cleaner including a rotatable cylindrical body with a brush seat therein, said seat having sides and each of said sides lying in a single plane which intersects said body and makes an angle of less than 90 degrees with the major axis thereof.

DALE C. GERBER.
EDWARD R. SWANN.
